SHEET PILING

Jonathan Roy Freeze, Middletown, Ohio, assignor
to The American Rolling Mill Company, Mid-
dletown, Ohio, a corporation of Ohio

Application March 14, 1938, Serial No. 195,829

9 Claims. (Cl. 61—58)

This invention relates to sheet piling and more particularly to corrugated sheet piling. This corrugated sheet piling is intended for, and serves the same purpose as any piling now on the market. It has long been appreciated that the value of corrugation in a piling section is considerable and probably, the lack of universal acceptance of patented corrugated piling designs may be ascribed to poor joint construction. The attempt 10 has apparently been in the past, to follow, in connection with corrugated sheet piling, the joint practice established in connection with sheet piling according to what may be termed "rolled shaped practice". This is evidenced by attempts 15 to simulate the claw-like construction of joints in rolled shapes. This practice has resulted in weak, complicated, and relatively expensive joints. A further result of this practice has been that in the manufacture of hot rolled piling shapes, strength has been concentrated at the 20 joints because of the ease of manufacturing such joints when the metal is in a hot and soft state and, therefore, narrow panels with frequent joints have been the rule.

With the above considerations in mind, it is 25 an object of my invention to provide a corrugated sheet piling in which the panels may be broader than conventional which, of course, results in more expeditious erection and greater 30 simplicity. It is a further object of my invention to provide a novel joint for adjacent panels which will have improved sealing qualities.

It is another object of my invention to provide 35 corrugated sheet piling, in which the sections will be readily nestable for shipping purposes, which will have a great column strength and resistance to turn-over on the driving end, which will have great beam strength distributed across the entire width of the panel instead of being 40 concentrated at the joints and which will be extremely versatile in that, it may be fabricated from a large variety of mill structures involving a range of gauges and metallurgical properties.

These and other objects of my invention which 45 will be pointed out more specifically hereinafter or which will be apparent to one skilled in the art upon reading this specification, I accomplish by that certain construction and arrangement of parts of which I shall describe certain exemplary 50 embodiments.

Reference is now made to the drawings forming a part hereof, and in which:

Figure 1 is an end view of a panel of corrugated 55 sheet piling.

Figure 2 is a plan view of the same.

Figure 3 illustrates one type of joint between adjacent sections.

Figure 4 illustrates a different type of joint adapted to have a sealing material joined into it.

Figure 5 shows a slightly different piling section and a joint between two adjacent sections designed for certain uses.

Figure 6 is a cross sectional view of a locking piece for joining together piling sections meeting 10 at right angles.

Figure 7 is an end view of a slightly different locking piece.

Figure 8 is an end view of still another form 15 of locking piece.

Figure 9 indicates an end view of a number of piling sections joined together and swung about an arc of a large radius.

Briefly, in the practice of my invention, I provide piling comprising a plurality of corrugated 20 sections. The lateral edges of the respective panels are reversely bent to form joining elements and certain shaped locking pieces are provided for the purpose of joining piling sections which meet at right angles or similar large angles. 25

In Fig. 1, I have shown a panel 10, of corrugated sheet material in which the end portions 11, are provided with reversely bent parts 12. A joint between two such adjacent panels 10, is shown in cross section in Fig. 3. It will be noted that the panel in Fig. 1, is such that adjacent panels will have to be reversely placed in order to provide for the interlocking joints and it follows from this that in closing a circle or the like, an even number of panels will be required. It 30 is to be understood that an odd number of panels may be used by the simple expedient of providing reversely bent portions on parts of the panel extending parallel to each other as illustrated, for example, in Fig. 5. In this figure the panel 20, is provided at the left end 21, with a reversely bent portion 22, and at the right hand end 23, it is provided with a reversely bent portion 24.

The joint between the panel sections illustrated, for example in Fig. 3, may be made for a 45 snug driving fit, so that the joint may be tight when driven or it may be modified as shown in Fig. 4. In this figure the two panels 10a, are joined at their ends, 11a, where they are provided with reversely bent portions 12a which, however, are bent somewhat in a hair pin shape. It will be clear that in this type of joint, the portions 13, may be filled with any type of sealing material for the purpose of providing a completely water tight joint. 50 55

Another minor joint modification is illustrated in Fig. 5 where the spacing between the arms 23 and 23a and 24 and 24a, is greater than that illustrated in Fig. 3. This construction permits adjacent sections to be placed at a slight angle to each other illustrated by the angle A. In this manner, a gradual curve may be simulated as exemplified in Fig. 9.

Where adjacent panels meet at a right angle, it is necessary to provide joining or locking members or clips as will now be described.

Figure 6 illustrates a clip 30, for joining together two panels 31 approaching each other at substantially a right angle. It is to be noted that the sections 31 in Fig. 6, are of the type described in connection with Fig. 5, that is, adjacent sections need not be reversed for joining. Fig. 7, shows a slight modification in which the member 30a is off-set as indicated at 32. This type of clip or joining piece is preferable where the angle of adjacent panels is much greater than 90° since it prevents the piling from coming apart. It will be clear from a consideration of Fig. 6, that if the upper panel 31 were swung to the right so as to make the angle greater, the upper member 31 could swing out from the upper portions of the clip 30. The off-set 32 in Fig. 7 effectively prevents this.

The joining clip 33 shown in Fig. 8, is provided for the purpose of joining adjacent sections approaching each other at right angles where the sections are of the type illustrated in Fig. 1.

It will be clear that by this construction a large variety of gauges and metallurgic properties may be employed to suit the particular emergency of the occasion and it is to be understood that gauge and material do not form limitations upon my invention. It will be clear that various modifications may be made without departing from the spirit of my invention and that I do not intend to limit myself otherwise than is pointed out in the claims which follow.

Having now fully described my invention what I claim is new and desire to secure by Letters Patent, is:

1. Sheet piling comprising a number of panels of corrugated sheet metal, the lateral edge bends of each of said panels being provided with reversely bent flat portions of a length substantially equal to the slant length of a corrugation, said reversely bent flat portions of adjacent panels adapted to be interengaged to provide joints in said piling.
2. Sheet piling comprising a number of panels of corrugated sheet metal, said panels consisting of a number of whole corrugations, the lateral edge bends of each of said panels being provided with reversely bent flat portions of a length substantially equal to the slant length of a corrugation, said reversely bent flat portions of adjacent panels adapted to be interengaged when adjacent panels are reversely disposed, to provide joints in said piling.
3. Sheet piling comprising a number of panels of corrugated sheet metal, said panels comprising

a number of whole corrugations plus one-half corrugation, the lateral edge bends of each of said panels being provided with reversely bent flat portions of a length substantially equal to the slant length of a corrugation, said reversely bent flat portions of adjacent panels adapted to be interengaged to provide joints in said piling.

4. In sheet piling according to claim 2, in which two sections meet at an angle in the vicinity of a right angle, a joining clip comprising a strip of metal having two limbs disposed at the angle at which said sections meet and each of said arms having reversely bent portions extending substantially parallel to said arms within said angle.

5. In sheet piling according to claim 3, in which two sections approach each other at an angle in the vicinity of a right angle, a joining clip comprising a strip of metal having two arms disposed at the angle at which said sections approach each other, each of said arms being provided with a reversely bent portion disposed parallel to said arms, one of said portions being within the angle and the other being outside the angle.

6. In sheet piling according to claim 1, in which two sections approach each other at an angle greater than a right angle, a joining clip comprising two hook portions having parallel arms, said hook portions being connected by an off-set portion to prevent disengagement of said clip from said sections.

7. In sheet piling according to claim 3, in which two sections approach each other at an angle greater than a right angle, a joining clip comprising two hook portions having parallel arms, said hook portions being connected by an off-set portion to prevent disengagement of said clip from said sections.

8. Sheet piling comprising a number of panels of corrugated sheet metal, the lateral edge bends of each of said panels being provided with reversely bent portions, said reversely bent portions of adjacent panels adapted to be interengaged to provide joints in said piling, said reversely bent portions being respectively parallel to said lateral edge bends and spaced therefrom a distance greater than that necessary to accommodate the corresponding portions of an adjacent panel, whereby adjacent panels may be disposed at slight angles to each other to simulate a curve of large radius.

9. Sheet piling comprising a number of panels of corrugated sheet metal, the lateral edge bends of each said panels being provided with reversely bent portions, said reversely bent portions being spaced from said lateral edge bends a distance sufficient to accommodate the corresponding portions of an adjacent panel, and said reversely bent portions being spaced from said lateral edge bends at the bend a distance greater than that necessary to accommodate the corresponding portions of an adjacent panel, whereby areas of roughly wedged shape in cross section are provided when said adjacent panels are interlocked.
